UNITED STATES PATENT OFFICE.

HERMAN E. S. CHAYES AND AUGUST P. JURGENSEN, OF NEW YORK, N. Y., ASSIGNEES
TO CHAYES DENTAL INSTRUMENT CORPORATION, OF NEW YORK, N. Y., A COR-
PORATION OF DELAWARE.

DENTAL TOOL HOLDER.

Application filed October 10, 1925. Serial No. 61,644.

This invention relates to a dental tool holder, particularly adapted to be connected with and operated by a dental handpiece.

The object of the present invention is to provide an improved form of tool holder having a simple and effective means for locking or releasing the shaft of the tool and having means whereby the tool holding part may be secured in different angular positions with respect to the handle member of the holder.

The invention consists in a dental tool holder in which the shaft of the tool is held in place by means of a jaw member normally engaging a groove in the tool shaft and connected with means manually operable to move the jaw member out of engagement with said groove to permit removal of the tool.

The invention also consists in a dental tool holder which comprises a tool holding part in which the tool is rotatably mounted, and a handle member, said part and member having cooperating joint members permitting connection of said part with said member in a plurality of different angular relations.

Other subsidiary features of the invention will be clearly set forth in the appended claims.

In the drawings, in which a preferred embodiment of the invention has been selected for illustration:—

Fig. 1 is a view in side elevation of a dental tool holder constructed in accordance with the invention.

Fig. 2 is a view in longitudinal section of the tool holder shown in Fig. 1.

Fig. 3 is a plan view of a portion of the tool holder shown in Fig. 1.

Fig. 4 is a similar plan view of the tool holder with the cover plate removed.

Fig. 5 is an end view of the tool holding part of the tool holder.

Fig. 6 is a view in vertical section of a tool holding chuck forming part of the invention.

Referring to the drawings for a more detailed description of the invention, at 10 is shown a hollow handle or attaching member which is adapted to be fitted to the tapering forward end of a dental drill head or handpiece 10^a to form an extension thereof. The handle member 10 has a knurled hand-grasping portion 11 and, at its forward end, ter-

minates in a joint member 12 inclined at an angle to the axis of the handle member. A pair of diametrically opposite lugs 13 on the inclined face of the joint member 12 are adapted to enter diametrically opposite slots 14 of a plurality of pairs of such slots formed, as shown in Fig. 6, in the end face of a joint member 15 forming the terminal portion of the tool holding part 16 of the tool holder. This arrangement shown, having two pairs of slots 14, provides for the positioning of the drill holding part 16 in one of four different angular positions with relation to the axis of the handle member, the joint members being held in interlocked relation by means of the threaded sleeve 17.

The drill holding part 16 of the holder forms a bearing member in which a driving shaft 18 is journaled, the shaft terminating at its forward end in a bevel pinion 19 meshing with a geared flange 20 on a tool holding chuck or socket 21. The chuck 21 is journaled for rotation about an axis at right angles to the axis of the shaft 18 and has a bearing support at 22 in the chuck holding head 38 for its upper end, the lower end being supported by the bearing member 23 which has a threaded engagement with an end of the bore 24 in which the chuck 21 is arranged. An oil hole 39 is provided for supplying lubricant to shaft 18 and other bearing parts.

The shaft or arbor 25 of the tool is placed in the bore of the chuck 21, and the upper end of the shaft is cut away to approximately the axis of the shaft to provide a flat surface 26, Fig. 5. The upper end of the bore of the chuck is formed complementarily to provide a similar flat surface, and through the engagement of these flat surfaces the shaft 25 is rotated with the chuck to rotate the grinding stone 27 or other tool carried by the shaft. The shaft 18 is driven through a universal joint connection at 28 with a shaft 29 extending through the handle member 10 and adapted to be engaged or gripped by the chuck of the drill head or handpiece 10^a on which the handle 10 is adapted to be mounted.

In order to lock the tool shaft 25 in operative position within the driving chuck 21, a latching device 30 is employed which includes a pair of jaw members 31 arranged to engage within the opposite sides of a

groove 32 formed in the tool shaft 25 adjacent the upper end thereof. The jaw members 31 are integrally connected with the base 34, which is bent upwardly at the end 5 thereof opposite the jaw members and then again bent horizontally parallel with itself as clearly shown in Fig. 2. The latching device so formed is slidable upon an upper surface 33 of the part 38, within a chamber 10 formed above this surface and normally closed by a cover plate 35.

The cover plate 35 has a knurled or roughened upper surface, as shown in Fig. 3, and is attached to the latching device by means 15 of the screw 36, so that by pressing the cover plate rearwardly the jaws of the latching device may be removed from engagement with the tool shaft 25 and the latter may be removed. When a tool shaft has 20 been inserted in place in the chuck and the pressure on the cover plate is released, a spring 37 returns the cover plate to closed position and also returns the latching device into position to hold the tool shaft in 25 place in the chuck. The cover plate is slidably mounted by having dovetailed engagement at its edges with the walls of the part 38 enclosing the chamber in which the latching device is arranged. The interior surface 30 of the handle member 10 is of tapered form to fit over the forwardly converging end of a dental handpiece 10^a, as shown in dotted

lines in Fig. 2, and the end of the handle member is preferably slotted at the end at 39' to pass over a screw 40 on the handpiece 35 to prevent rotation of the handle member, and may be transversely slit at 41 to provide a gripping engagement with the handpiece.

The parts 10 and 15 of the device are preferably formed of light-weight metal such as duralumin, while the main bearing portion 16 is formed of stainless steel, bronze or the like. The various joints are closely fitted and in the drill holding relation of parts no 45 openings are available in which the moisture can enter when the device is in use.

What is claimed is:—

1. In a dental angle piece, a drill-carrying member, a chuck mounted in said member for receiving a drill, a recess in said member, a latching member slidable in said recess for retaining the drill, said latching member having an upwardly and forwardly extending arm and a sliding cover secured to the forwardly extending arm of said latching member and normally closing said recess. 50

2. A device as set forth in claim 1 in which a spring is mounted in said recess for maintaining said cover in closed position. 55

In testimony whereof we affix our signatures.

AUGUST P. JURGENSEN.
HERMAN E. S. CHAYES.
